(57) **CLAIM**

The ornamental design for a parking terminal, as shown and described.

DESCRIPTION

FIG. 1 is a perspective view of a parking terminal;

FIG. 2 is a front view of the terminal of FIG. 1;

FIG. 3 is a rear view of the terminal of FIG. 1;

FIG. 4 is a right side view of the terminal of FIG. 1;

FIG. 5 is a left side view of the terminal of FIG. 1;

FIG. 6 is a top view of the terminal of FIG. 1; and,

FIG. 7 is a bottom view of the terminal of FIG. 1.

The broken lines in the drawings are included for illustrating portions of the parking terminal that form no part of the claimed design.
